UNITED STATES PATENT OFFICE.

ARNOLD J. GRAFENSTATT AND WILLIAM TWEEDIE, OF MINNEAPOLIS, MINN.

SODA-MOTOR.

SPECIFICATION forming part of Letters Patent No. 350,428, dated October 5, 1886.

Application filed May 21, 1886. Serial No. 202,929. (No model.)

To all whom it may concern:

Be it known that we, ARNOLD J. GRAFENSTATT and WILLIAM TWEEDIE, citizens of the United States, residing at Minneapolis, Hennepin county, State of Minnesota, have invented certain new and useful Improvements in Soda-Motors, of which the following is a specification.

Our invention was especially designed to meet the requirements of rapid-transit street-railways, which run a greater or less portion of their course on thoroughfares in the midst of a dense population. Dummy steam-engines were so objectionable on account of noise and smoke as to amount to a nuisance. A motor was demanded which would be noiseless, free from smoke, capable of continuous use, economical in cost of running, and capable of being compactly built in small compass. Soda-motors met these requirements in a measure, but as constructed prior to our invention developed defects and limitations peculiar to themselves, which it is the object of our invention to overcome.

Our invention relates to "soda-motors," so called, in which caustic soda, potash, concentrated lye, or other similar material is used as a fuel or means for generating steam; and it has for its object to evaporate the water and moisture from the soda or other chemical without the discharge of the soda from the boiler of the soda-motor, and to produce a constant, efficient, and cheap power for engines.

As now used, the soda comes from the factory in solid blocks incased in metal. At the fixed station this is liquefied and heated to a very high degree, 230° or 240° centigrade. It is then run by pipes into the soda-boiler of the soda-motor, where it acts as a fuel or reservoir of heat, generating steam from the steam-boiler on the motor. The steam is then applied in the ordinary way, with this important difference—viz., the exhaust-steam is conducted into the soda-boiler. This exhaust-steam is so disposed of chiefly for the reason that the soda has a limited high absorbent power for steam, serving as a vacuum for the reception of the exhaust-steam, thereby avoiding the work of resistance to the atmospheric pressure required when the exhaust is made into the air. This the soda will do for a limited time—i. e., up to the point when it be-

comes charged with moisture. Then a back-pressure will begin to be shown in the soda-boiler from the surplus steam and the soda loses its power as a fuel or steam-generator. The soda has then to be withdrawn and the moisture evaporated before it can again be used. This is now done at the fixed station by the application of superheated steam. Meantime, or until other soda before prepared is placed in the soda-boiler, the engine must stand idle.

Owing to the limit in time within which the soda will act as a fuel before becoming supercharged with moisture, the soda-motor is only suitable for short trips, and must return within the limit to the fixed station, where expensive appliances are necessary to prepare and replace the soda. It is to overcome these defects in the present soda-motor, and to enable the use of the same soda indefinitely without removal from the boiler, with the consequent great saving of time, labor, and expense, that we have made our invention.

By our invention we evaporate the moisture from the soda while in position in the boiler. We do this by the application of heat. The means herein shown and described are a series of jets placed under a caustic-soda boiler, which are supplied through pipes with oil or gas or spirits from suitable tanks. Any other suitable means for applying the heat may be employed. The means herein shown we have conceived and perfected and claim as of our sole invention; but we do not desire to be limited to these means alone, but claim the process, by whatever means applied.

In accompanying drawings, Figure 1 is a side elevation, and Fig. 2 is an end view, of the two boilers as designed by us to be used for the soda-motor, showing the construction employed by us for applying our process.

Similar letters of reference refer to like parts throughout.

A is the upper half of cylinder and is the steam-boiler.

B is the lower half of the cylinder and is the soda-boiler containing the caustic soda, potash, concentrated lye, or other chemical which is used as a fuel to generate steam.

c c c is an oil-tube provided with a number of burner-jets and communicating with oil tanks or reservoirs, which are securely placed

in any convenient position above the line of jets. Stop-cocks are placed on the communicating oil-tubes at any convenient points intermediate the tanks and line of jets for controlling the supply of oil. Any suitable illuminating oil or gas or spirits may be used—such as gasoline, common gas, benzine, camphine, kerosene, paraffine, naphtha, turpentine, alcohol, or tallow, &c.

10 D D are escape-pipes for the evaporated moisture, and are attached to the soda-boiler B at any suitable convenient point. These escape-pipes are provided with stop-cocks, so as to close off the evaporation whenever the 15 soda reaches the required temperature.

15 F F is a box under the soda-boiler, in which the jets are placed in proper position for heating the boiler B.

20 E E are ventilation-tubes attached to the box F F and leading to the air or any convenient place.

Under the box F F is a ventilation door or slide for supplying the air requisite for combustion.

25 Any number of oil-tubes with jets may be placed under the soda-boiler and within the box F F, according to the need.

The boilers A and B may be arranged in any suitable and convenient position with reference to each other. The steam-boiler A may have any number of flues suspended into or passing through the soda-boiler, or may have any other suitable construction to give it a large heating-surface. This boiler is of a 35 special construction, (not herein fully described,) invented by us for this especial purpose, and we reserve the right to apply for a patent on the same in another application. The exhaust-steam from the engine is conducted into the soda-boiler by pipes. (Not shown in the drawings.)

The engine (not shown) may be any ordinary steam-engine.

In operation, by our process and construction, whenever the soda becomes so charged with moisture or ceases for any reason to act as a fuel or steam-generator the attendant engineer simply opens the escape-pipes D D, turns on the oil or gas from the tanks by 45 the proper stop-cocks, and lights the jets. In a short time the moisture will have been evaporated and the soda reheated to a high degree of heat. The escape-pipes may be then closed and the jets turned off, and the 55 caustic soda is again ready to act as in the first place. In practice we would not wait until the soda entirely ceases to act, but, on the contrary, would apply our process the moment that the gage began to show back-pressure in 60 the soda-boiler. Thus the engine need not be stopped, but may be run indefinitely, the same process being repeated whenever required while the train is in motion. The fixed station, with all its expensive appliances for preparing and repreparing the caustic soda, is entirely done away with, and the limitations to the present soda-motor are removed.

A material part of our invention, upon which we place high value and for which we seek protection, is the joint application of caustic 70 soda or other chemical having the qualities requisite to give the necessary body, and oil, gasoline, gas, spirits, petroleum, or their equivalent, which, when burned, give the necessary intensity, the two together making a steam-generator far superior to either alone or to wood or coal. Soda alone could not be used, save only as is now done on the old soda-motor—i. e., merely as a reservoir of heat. Oil, gas, gasoline, and spirits when used alone 80 have great intensity, but little body. We claim to have been the first to have discovered that the one supplies just what the other needs, and to have applied this principle to the generation of steam. 85

The great intensity of the heat from the oil, gas, or their equivalent quickly raises the soda to the required initial temperature or evaporates the moisture and restores the heat after supercharge, thus enabling the engine to be 90 run a far greater portion of the time without fire, avoiding smoke and the blast-noise nuisance during the short interval when the fire is used, securing a great saving in time, a compactness of construction saving much space 95 and weight, and enables the continuous use of the engine. Wood or coal will not raise the soda to a high temperature quickly, but require a long time, for the reason that the fire must be kindled and a large bed of live coals accumulated before the heat becomes sufficiently intense to become effective. 100

In the foregoing specification we have described our process as applied to locomotives. It will of course be understood that it is just 105 as applicable to stationary engines, and generally wherever it is required to generate steam.

We desire protection on the entire process herein shown and described and on the means 110 and all equivalent means of applying the same.

We claim, broadly, as our invention—

1. The process of the continuous generation of power by the use of caustic soda or equivalent, which consists in applying said caustic 115 soda or equivalent in a heated condition to the boiler within an inclosing-case, and regenerating and reheating said caustic soda or equivalent, when desired, by applying heat to the exterior of said inclosing-case, substantially as described.

2. The novel process herein disclosed for producing and utilizing power, consisting in (a) raising caustic soda or other equivalent chemicals to a high initial temperature and 125 evaporating the moisture from the same by means of oil, gas, gasoline, spirits, or petroleum burned directly underneath the reservoir containing said soda; (b) applying the heat from the caustic soda to the steam-generator; (c) applying the steam thus produced through the ordinary engine; (d) absorbing the exhaust-steam from the engine into the caustic soda up to the point of supercharge; (e) the reconcen- 130

tration of the soda and restoration of initial temperature whenever required by step (a) without removal of the soda from the boiler.

3. The combination of a combustion-chamber containing a series of jets for the burning of oil, gas, gasoline, spirits, or petroleum, a boiler containing caustic soda or other equivalent chemicals, and a steam generator or boiler containing water, said caustic-soda boiler being placed intermediate the jets and the steam-boiler and in immediate contact with each substantially as described, for the purpose set forth.

4. Means, substantially as described, for applying heat to a soda-boiler when in working position on a soda-motor, in combination with means for allowing the escape of the evaporated moisture from the soda-boiler, for the purpose set forth.

5. Means, substantially as described, for applying heat to a soda-boiler when in working position on the soda-motor, in combination with means for allowing the escape of the evaporated moisture from the soda-boiler, and means for controlling the supply of heat and the escape of the moisture, for the purpose set forth.

6. A series of tubes provided with jets, means

for supplying oil or gas to the same, a soda-boiler in working position on a soda-motor, and escape-pipes for the evaporated moisture, all in combination, for the purpose set forth.

7. A series of tubes provided with jets, means for supplying oil or gas to the same, a soda-boiler in working position on a soda-motor, escape-pipes for the evaporated moisture, and means for controlling the supply of oil and gas and the escape of the evaporated moisture, in combination, for the purpose set forth.

8. A series of tubes provided with jets, means for supplying oil or gas to the same, a soda-boiler in working position on a soda-motor, escape-pipes for the evaporated moisture, means for controlling the supply of oil and the escape of the evaporated moisture, a combustion-chamber underneath the soda-boiler provided with means for supplying the air necessary for combustion, all in combination, substantially as described, for the purpose set forth.

ARNOLD J. GRAFENSTATT.

WILLIAM TWEEDIE.
